POL RAVIGNEAUX, OF NEUILLY-SUR-SEINE, FRANCE.

CLOSING DEVICE FOR BELTS.

Application filed November 10, 1924, Serial No. 748,962, and in France November 23, 1923.

The present invention relates to a buckle for attaching belts, girths or various ribbons.

The said buckle is so disposed that the insertion of the band into its openings and the bending of the same upon the parts of the buckle will permit the formation between the edge and the buckle of a sort of regular knot, which is held in place by the tension of the band itself.

The principal advantages of the said buckle consist in the first place in the fact that it may be made in a single piece which is suitably apertured, and without any joints, so that the said buckle may consist of composition material or metal, or even of a semi-rigid material such as leather.

Since it possesses no mechanical parts, it has the simplest possible construction, and by reason of the absence of joints it is not subject to wear. As regards its application, the tongue of the buckle is eliminated, and thus there will be no risk of wounding the person.

In the known forms of tongueless buckles, the leather of the belt is usually deteriorated within a short time, since it is held between two metal pieces which must often be roughened to prevent slipping.

But in the device according to the invention, the leather of the belt is held upon the buckle—which may be well polished—solely by its own means. Inasmuch as the combination of the buckle and the belt is very flat since only one piece is employed, it can be substituted to advantage for the buckles with tongues or for buttons provided with an eyelet which are employed in orthopedic devices.

In the appended drawings which are given by way of example:

Fig. 1 shows a constructional form of the device according to the invention, with a ribbon or band knotted upon the buckle.

Fig. 2 is a sectional view showing the manner in which one of the portions of the band is held by the other.

Fig. 3 is a modification in which the buckle is differently apertured.

Fig. 4 is a simplified form.

Fig. 5 is a modification in which certain of the apertures in the buckle are opened to the exterior.

Fig. 6 is a modification in which the up-

per edge of the frame of the buckle has the 55 oblique position.

Fig. 7 shows a buckle made of a continuous metal wire.

Fig. 8 shows two buckles united in one and having a common aperture. 60

Fig. 9 shows a buckle in which the edge of the second bending is encircled.

The closing device according to the invention may be used for belts or girths which are made in one piece, as well as for attaching two separate pieces, as for example in the tightening straps at the back of trousers, but for the sake of clearness the following description relates to a closing device for a belt. 70

The portions of the belt will be designated as follows. The entering portion, the one which is brought to the buckle before any folding occurs; the folded portion, the one proceeding from the first to the second fold; 75 the outgoing portion, the free end leaving the buckle; the closing portion, the part of the belt connected to the buckle after passing around the body. The lower face of the buckle signifies the face situated next to the body, and the upper face signifies the external face when the said buckle is in position.

The principal elements of the buckle are an input aperture C through which the belt 85 is inserted, an output aperture B¹ upon whose edge E it is folded or bent for the first time, a frame upon whose edge D the belt is folded a second time, a lug N by which the operator may conveniently hold 90 both the belt and the buckle while a knot is tied, and an aperture B² to which the closing portion is attached.

The width of the input aperture C, the distance between the two apertures C and 95 B¹ and the inclinations of the edges of the said apertures combined with those of the edges E and D, are the important elements of the invention.

Fig. 1 shows the manner in which the knot 100 is made upon the buckle. The band which has been inserted through the input aperture from bottom to top and is then bent upon the edge of the output aperture and thus returns below the buckle; it is then bent upon the straight edge D of the buckle so that it will return upon the outside of the frame, and the end is brought under the 105

part of the band situated between the two apertures C and B¹, in such manner as to form a knot. The flatwise tightening serves to prevent the band from slipping. It should be remarked that due to the inclinations selected for the folding edges, which are straight, the belt will be properly folded at each edge, without wrinkling or improper folds, and the output strand will be placed directly between the input and the output apertures.

But the several elements of the buckle may be so combined that the band will be tightly held by other means. If the distance between the lower points I and J of the two apertures is substantially equal to the width of the band taken in the direction I J, the band will also be held in the transverse direction. If on the other hand the inclination of the external edge of the first aperture C and that of the internal edge of the second aperture B¹ are so combined that the belt, after having been twice bent, as above stated, is brought out parallel to the external edge of the first aperture, and if the latter is given a suitable width according to the thickness of the buckle and the thickness of the band, the edge of the outgoing portion will be held upon the whole length of the internal edge of the said aperture, so that the belt will be tightly maintained.

The force which acts against the loosening of the band is multiplied upon the entering portion, since the belt is wound upon the buckle as a cord is wound upon a cylinder. For this reason, the second aperture B¹, or rather the edge E against which the band is bent, which is the only one operative, is given a more inclined position than the edges of the first aperture both of which are operative in this case and are substantially parallel.

Fig. 2 is a section corresponding to Fig. 1, showing the manner in which the outgoing portion is held in the first aperture. Fig. 1 further shows a lug N situated outside the portion of the buckle serving to support the knot. The said lug is not simply employed to give an attractive appearance, and to form a rectangle, but when the belt is put on, it enables the entering portion to be held between two fingers while the knot is completed with the other hand. As a rule, it is suitably cut out, so that the band will be better held.

The closing portion of the belt may be also maintained by a catch or clasp forming a hook, and in this event the knot which is formed at the other end serves solely to adjust the length.

The said closing portion is brought through the aperture B²; the end may be sewed in the known manner or preferably maintained by two rivets, as observed. The latter may be replaced by any desired re-

movable means, for instance by spring buttons. This side of the belt may also be made adjustable, although this is not necessary, since any person can adjust the belt to the suitable length about the waist by cutting the end of the belt, in such manner that the free end will not hang down in an inconvenient position.

If the buckle is made of metal or of a rigid composition material, it may be given a cylindrical convex shape so as to fit upon the body, or a spherical convex shape in order to increase the rigidity, and this will allow of reducing the thickness to some extent. If a semirigid material is employed, such as partially hardened leather or india rubber, the closing portion of the belt can be sewed to the buckle, or it may even be constituted by the same piece, provided the end at which the knot is made is sufficiently thin to be bent.

Fig. 3 shows the same buckle, from which the portion separating the two apertures B¹ and B² has been removed so that the latter will now form a single aperture B; the principle is not changed, but this allows of some reducing the length (since no tongue is required at the upper part) and also of lightening the buckle, which may prove advantageous, both as regards cost and wear.

Fig. 4 shows a simplified device in which the lug N is eliminated, and this arrangement may suffice for particular uses, such as for girths.

Fig. 5 represents a buckle in which the apertures B and C are opened at the top. For certain uses, in order that the device may be put in place more rapidly, either or both of the said apertures may be opened at the top or bottom, according to the case.

Fig. 6 shows a buckle in which the upper part of the frame, on which the second fold is made, has an oblique position. By a suitable choice of this inclination, the outgoing portion of the band may assume any inclination, but in order to maintain the characteristics of the buckle, the inclination of the edge D must always be combined with the inclination of the external edge of the aperture C and of the internal edge E of the aperture B¹. The figure shows the outgoing portion falling vertically.

Fig. 7 represents a buckle according to the invention which is made of bent wire, and certain portions may be soldered together at suitable points. This buckle has the same features as Fig. 1, and more particularly Fig. 3, and comprises an aperture C and the folding edges E and D having suitable sizes and positions, also comprising the lug N.

Fig. 8 shows a double buckle, in which the two ends are individually maintained. As a particular case, the same aperture B² with parallel edges serves for the first fold of each end, so that the knots will be symmetrical,

one portion of the band leaving at the top and the other at the bottom. The buckle may obviously be combined in such manner that the two knots will be entirely independent.

The buckle of Fig. 9 comprises, besides the apertures and the ordinary edges of binding, a frame which can serve both for protecting the band and for ornamenting the buckle.

The buckle as above described may also serve to secure and support a knot which is not tightened, for instance as applied to clothing, hats or the like, and instead of employing a closing portion of band, the buckle may be attached to the objects in question.

Having thus described my process and apparatus, what I claim as new therein, and my own invention, is:

A buckle adapted to join the two ends of a belt, the said buckle comprising an input aperture adapted for the insertion of the

said belt, an output aperture having a straight internal edge and adapted for the insertion of the said belt, an output aperture having a straight internal edge and adapted for the insertion of the end of the belt issuing from the said input aperture, a straight edge of the buckle making with the internal edge of the said output aperture such an acute angle that the free strand of the belt, after having been folded around the said edges has such a direction that it directly proceeds in the space comprised between the said apertures, the external edge of the said input aperture being straight, making an acute angle with the internal edge of the said output aperture and having an inclination which is substantially parallel to the free strand of the belt.

In testimony that I claim the foregoing as my invention, I have signed my name.

POL RAVIGNEAUX.
